Primary Examiner—Charles A. Rademaker

(74) Attorney, Agent, or Firm—Wallenstein Wagner & Rockey, Ltd.

CLAIM

The ornamental design for a disposable plate, as shown and described.

DESCRIPTION

FIG. 1 is a top perspective view of a disposable plate showing our new design;

FIG. 2 is a top plan view thereof;

FIG. 3 is a left side elevation thereof;

FIG. 4 is a right side elevation thereof;

FIG. 5 is a bottom plan view thereof; and,

FIG. 6 is a top plan view of modified embodiment of the design shown in FIGS. 1 through 5, the other views thereof being mirror images of FIGS. 1 through 5.

The broken lines shown in the drawings represent environment and for no part of the claimed design.

1 Claim, 3 Drawing Sheets
